UNITED STATES PATENT OFFICE

HUGH LOWERY, OF ALTON, ILLINOIS, ASSIGNOR TO STANDARD OIL COMPANY, OF CHICAGO, ILLINOIS, A CORPORATION OF ILLINOIS

REMOVAL OF WAX FROM HYDROCARBON OILS

No Drawing.

Application filed October 27, 1928. Serial No. 315,597.

This invention relates to the removal of wax from hydrocarbon oils and particularly lubricating oils containing slop wax, that is wax of properties and molecular weight intermediate those of paraffin wax and petro-
5 latum.

The lubricating oil to be treated may be a heavy lubricating distillate constituted by the cut between 80% and 90% off on Mid-
10 Continent crude. Such a cut has a viscosity between 75 and 120 seconds Saybolt at 210° F. The invention is not intended to be limited to the treatment of this particular cut since it is applicable to any hydrocarbon
15 distillate containing substantial quantities of slop wax.

When such a wax-containing distillate is diluted with naphtha or other suitable diluent and allowed to settle at low temperatures,
20 the separation of wax and oil is very unsatisfactory since only a relatively small quantity of oil can be recovered. I have now discovered that if a relatively small quantity of petrolatum is added to the diluted oil,
25 the separation is greatly improved and much greater yields of lubricating oils are obtained.

The invention will be more readily understood from the following specific example:
30 A distillate containing slop wax, constituted by the cut between 84% off and 87% off from Mid-Continent crude, having a viscosity of about 90 seconds Saybolt at 210° F., solid between 80° F. to 110° F. and containing be-
35 tween 7 to 12% of wax of the slop wax type is diluted with about 70% of naphtha of about 400° F. end point. A small amount, for example, between 1 and 5% of petro-
40 latum derived from steam refined cylinder stock by settling or centrifuging, having a melting point between 120 and 160° F. and containing between 30 and 70% of oil, is added to the naphtha solution. The solution is now slowly chilled to 10° F. and main-
45 tained at that temperature for between 60 and 80 hours. During this time the wax settles out leaving a supernatant layer of clear oil amounting to between 70 and 80% of the whole. After removing the naphtha the oil
50 has a pour point of about 40° F.

By way of comparison it may be stated that if the petrolatum is omitted only about 20 or 25% of clear supernatant oil separates under the same conditions and no variation of the amount of diluent, time or tempera-
55 ture, of settling improves that result.

The settled oil is reduced to remove the diluent and can be acid treated and finished in the usual way. For example, the oil may be treated with sulfuric acid, clayed and fur-
60 ther wax may be removed therefrom if de-
sired.

The distillate from which wax is to be re-
65 moved may be treated and clayed to color
before settling. In this case the petrolatum
used may be first purified to approximately
the same color as the oil to avoid contamina-
tion of the latter. This purification may suit-
70 ably be effected by filtering the petrolatum
through clay.

Although the present invention has been de-
scribed in connection with the details of a specific embodiment thereof, it is not intended that such details shall be regarded as limita-
75 tions upon the scope of the invention, except
in so far as included in the accompanying
claims.

I claim:

1. The method of removing slop wax from hydrocarbon oils containing same which con-
80 sists in diluting such oil with a relatively low boiling hydrocarbon oil, adding a small quantity of petrolatum thereto, chilling and allowing the wax to separate from the oil.

2. The method of dewaxing a petroleum oil lubricating distillate containing wax of the slop wax type, which consists in adding a light diluent to said distillate to reduce the viscosity and to thereby facilitate the settle-
85 ment of wax, adding between about 1 and 90 5% of petrolatum wax, chilling to a low tem-
perature and allowing the wax to settle out.

3. In the process of removing slop wax from hydrocarbon distillates containing such wax by diluting, chilling and settling, the 95 step of adding a small quantity of petrolatum thereto before said chilling and settling.

4. The method of dewaxing a petroleum oil lubricating distillate having a viscosity be-
100 tween 75 and 120 seconds Saybolt at 210° F.

and containing wax of the slop wax type
which consists in diluting said distillate with
between 65 and 80% of a naphtha of end point
not substantially over 400° F., adding be-
5 tween about 1 and 5% of petrolatum, chilling
to about 10° F., allowing to settle at such
temperature for 60 to 80 hours, and removing
the supernatant layer of oil.

10 In testimony whereof I have hereunto set
my hand and seal, this 24th day of October,
1928.

HUGH LOWERY.
